pany, Chicago, Ill., a corporation of Delaware

Application April 4, 1941, Serial No. 386,876

15 Claims.

(Cl. 105—315)

Room accommodations in railway passenger cars are rapidly increasing in popularity with the travelling public. Experience has shown that there is a great demand for single occupancy rooms, and there are in service, at the present time, a large number of cars provided with these rooms designed to furnish the occupant with the greatest possible riding comfort.

One type of single room proximates the dimensions of a single bed, and in its present form extends with its longest dimension extending lengthwise to the car. It is fully equipped, both for day and night use, with furnishings including a roomy seat disposed at one end of the room and extending transversely to the car. Directly behind the seat in the adjacent transverse room wall is a recess adapted to house a vertically extending bed pivotally mounted in the housing in such a manner that it can be rotated outwardly into the room to assume a horizontal position for night time use. In the car side wall is a large window extending throughout a substantial portion of the room length, which provides clear vision to the occupant of the seat. At the opposite end of the room is a hopper having an upholstered cover adapted to provide extra seating capacity in the room. In the transverse wall adjacent to the hopper is a folding washbasin movable into a wall recess when not in use. A wardrobe, a medicine cabinet, and other facilities may be provided in this last mentioned wall more thoroughly to equip the room for the convenience and comfort of the occupant.

Inasmuch as this room in size corresponds approximately to the length and width of the bed, both the seat and the hopper are made inaccessible when the bed is lowered to its position for use. The free end of the bed when lowered is closely adjacent to the room wall on the opposite side of the room from the bed recess, and the upper edge of the bed is disposed directly below the washbasin when the latter is in its open position. Thus, when the bed is lowered, the washbasin, when in its open position, projects over the bed and is very readily accessible to the occupant from a position on the bed.

Heretofore, it has been possible to open the washbasin when the bed is in its horizontal position. This condition is extremely undesirable, because, inasmuch as the hopper is rendered inaccessible by the bed the washbasin has been subjected to improper use.

The primary purpose of this invention, then, is to provide a simple locking device which effectively prevents opening of the washbasin at all times when the hopper is rendered inaccessible. This constitutes one of the principal objects of the present invention, others of which

include the provision of such a locking device which simultaneously functions to hold the bed in its position for use and one which is quickly and easily releasable to permit moving the bed to its inoperative position and renders the washbasin accessible only at times when the hopper likewise is accessible.

The above constitute some of the principal objects and advantages of the present invention, others of which will become apparent from the following description, in which,

Fig. 1 is a vertical transverse sectional view through a portion only of a roomette car, showing one of the transverse walls of a roomette; Fig. 2 is a fragmentary longitudinal sectional view through a roomette looking toward the aisle door;

Fig. 3 is a fragmentary longitudinal sectional view through a portion only of a roomette showing the bed in solid lines in its lowered operative position and further indicating in broken lines one position which the bed assumes when it is being moved between its operative and inoperative positions;

Fig. 4 is a fragmentary plan view of a portion only of a roomette showing the bed in its lowered operative position;

Fig. 5 is an enlarged fragmentary view in elevation of a portion only of the washbasin showing the combination hold-down and locking device in its unlocked position;

Fig. 6 is a vertical sectional view through the combination hold-down and locking device taken on the line 6—6 of Fig. 5;

Fig. 7 is a horizontal sectional view taken through the upper part of the locking device and showing a part of the washbasin;

Fig. 8 is a fragmentary vertical sectional view taken transversely through the bed when in its lowered position, the view being taken adjacent to the free end of the bed and showing a part of the casing housing the basin locking device broken away;

Fig. 9 is a vertical sectional view taken on the line 9—9 of Fig. 8;

Fig. 10 is a detail view corresponding to Fig. 9 and showing the latch in its released position to permit raising of the bed;

Fig. 11 is an enlarged perspective view of the wall support for the latch;

Fig. 12 is an enlarged fragmentary perspective view of the vertical lever which operatively connects the latch to the basin locking lever, and

Fig. 13 is an enlarged perspective view of the latch which actuates the basin locking lever and at the same time cooperates to hold the bed in its lowered operative position.

In compliance with section 4888 of the Revised Statutes, one specific embodiment of the present

invention is selected for the purpose of disclosure. Obviously, many modifications may be made without departing from the scope of the invention.

Referring to the figures, the invention is shown as applied to a railway car, generally indicated at 20 (Fig. 1), having outer side walls, one of which is shown at 21, a floor generally indicated at 22, and a roof 23. Extending lengthwise to the car along the center line thereof is an aisle 24 directly over which are ventilating ducts 25 and 26 forming parts of the conditioned air circulating system. On each side of the aisle 24 are a plurality of single occupancy rooms 27, and for the purpose of this application only one 15 of these rooms will be described.

Referring particularly to Figs. 1 and 2, each room is bounded by the car outer side 21, an aisle partition 28, and spaced transverse partitions, generally indicated at 29 and 30 (Fig. 2). A door 31 provides access from the aisle into the room, and, as shown, this door slides back into a recess 32 (Fig. 1) when it is opened. Some suitable handle 33 is furnished on the inside of the door and a mirror 34 may be attached to the inner face of the door for the convenience of the room occupant. A window 35 (Fig. 1) is provided in the car side wall 21, and is of sufficient length and height to give adequate light and view to the occupant.

Referring to Fig. 2, each room is supplied with a seat, generally indicated at 36, comprising a seat portion 37 and a back 38. This seat 36 extends crosswise of the room from the aisle partition 28 to the car side wall 21, and, though it is designed to give ample room for one person, it can very readily accommodate two.

Directly behind the seat 36 in the transverse partition 30 is a recess 39 extending from the lower region of the room vertically substantially to the ceiling. A bed 40 (Fig. 2) is pivotally mounted in the recess 39 in some suitable manner, as, for instance, by means of journals 41, and this bed can be lowered into the room by causing it to pivot about the journals 41 until it assumes the horizontal position indicated in broken lines 40'. The seat back 38 is pivotally mounted at 42 in some suitable manner to the outer face 43 of the bed 40, and as the bed is lowered the back 38 is caused to rotate with the bed until it assumes a position indicated in broken lines 44 underneath the bed. The seat back engages the outer face 43 of the bed at 45 when the bed is in its vertical position, but the seat back 38 is adapted to slide with respect to the bed so that it can assume the position shown in broken lines 44 when the bed is horizontal. Some suitable arm 46 is fastened to the lower edge of bed 40, and this arm, together with the pivot points 42, move the seat back 38 in response to the downward movement of the bed 40.

The bed 40 is counter-balanced by some suitable means, such as springs 47, secured to the lower edge of the bed by angle members 48 and anchored at the floor, as indicated at 49. A plurality of these counter-balancing springs 47 may be employed to properly counter-balance the weight of the bed to facilitate the opening and closing of the bed.

A shield 50 is fastened at one edge 51 to the lower end of the bed, and at its free end 52 it is adapted to slide in a vertical slot 53 provided in the transverse partition 30. When the bed is moved from its vertical position 40 to its hori-

5 zontal position 40', the shield 50 moves upwardly in slot 53 until it assumes the broken line position indicated at 54. This shield prevents bed clothing from dropping down into the recess 39 over the end of the bed.

Referring to Figs. 1, 2, and 8, the bed is made up of a pair of spaced sides 55 and 56, a foot end 57, and a head end 58 (Fig. 2). The bottom is enclosed at 59 in some suitable manner to hold a mattress (not shown) of sponge rubber or other suitable material.

At the opposite end of the room adjacent to the aisle partition 28 is a hopper 66 of standard size and closed by a cover 67 hinged to a stationary block 68 by a suitable hinge 69. Referring to Figs. 1 and 2, an upholstered back made up of sections 70 and 71 adapts the hopper for use as a seat when the cover 67 is closed, and, if desired, this cover may be cushioned and upholstered.

On the transverse wall 29 is a folding washbasin 72 above which is a shelf 73 and a medicine cabinet 74. Suitable lights 75 are positioned along the opposite vertical sides of a mirror 76 fastened to the outer face of the medicine cabinet 74. A wardrobe 77 is provided in the wall 29, and is of sufficient size to receive the normal wearing apparel worn by the room occupant.

Above the wardrobe 28 is a baggage rack 78 for supporting luggage.

Referring particularly to Figs. 2 and 7, the washbasin 72 comprises an outer or bottom face 79, a front face 80, a rear face 81, and a pair of side faces 82 and 83 (Fig. 1). Inside the basin is 35 a bowl 83 extending to the rear face 81 and forming a lip 84, from which the bowl contents are poured when the basin is raised to its vertical position shown in broken lines 72' in Fig. 2.

The basin 72 is pivotally mounted in a recess 40 85 (Fig. 2) formed in the transverse room wall 29. Any suitable means may be employed for pivotally mounting the basin, and, as shown, spaced trunnions 86 and 87 on each side of the basin are held in spaced arcuate slots 88 and 89, respectively, formed on the vertical sides of the recess 85. When the basin 72 is in its open position for use, as indicated in solid lines in Fig. 2, the trunnions 86 and 87 assume their positions in their respective slots or tracks at the extreme front and rear, respectively. As the basin 50 is rotated from the horizontal position to the vertical position indicated in broken lines 72', the lower trunnion 87 moves from its rearmost position to the foremost position in its track during the first part of the basin movement toward its closed position, the path of the trunnion being in the form of an arc with the upper trunnion 86 as the center of rotation, and during the last portion of the closing movement of the basin the upper trunnion 86 moves rearwardly in its passage to its rearmost position rotating about the lower trunnion 87, which, during this portion of the movement, is disposed at the forward end of its track. When the basin is closed, its outer face 60 79 is substantially flush with the room wall 29.

Directly below the recess 85 is a discharge chute 90 formed by four walls, two of which are indicated in Fig. 2 at 91 and 92. This chute empties into a pipe 93 which discharges below 65 the car.

On the back face 94 of the recess 85 is a suitable faucet assembly, generally indicated at 95, which is positioned over the basin 72 when the latter is in its open position, so that water issuing 70 75 from the faucet assembly 95 will flow into

the basin. Suitable faucet levers, one of which is shown at 86, are provided for hot and cold water.

When the basin is not in use, it is folded into the recess 85 to assume the position shown in Fig. 1 and in broken lines 72 in Fig. 2. To use the basin, it is necessary to grasp the handle 87 (Fig. 1) and lower the basin into the room, as shown in solid lines in Fig. 2. The basin is now in position for use and water issuing from the faucet assembly 85 will be held in the bowl 83. To empty the basin it is necessary to return it to its closed position shown in broken lines 72 in Fig. 2, and, as previously explained, the contents of the basin flow over the lip 84 and discharge from the car through the chute 80 and pipe 83.

Referring to Fig. 2, it is to be noted that the bed 40 when in its open position indicated in broken lines 41 extends from a position inside the recess 39 to the extreme opposite transverse wall 29. A supporting ledge 98 carries the weight of the free end of the bed when in its lowered position, and some means, which will be described presently, is utilized for holding the bed in this lowered position to overcome the counter-balancing force of the springs 47. These counter-balancing springs may be arranged to place the bed in a state of equilibrium when the bed is in an intermediate position between its fully open and its closed positions. The exact location of this position of equilibrium is not important for the purposes of this disclosure, but for illustrative purposes the position indicated in broken lines 99 (Fig. 2) has been selected to represent this condition. As the bed is being lowered, its weight tends to drop it to a position indicated by the broken lines 99, where the bed is balanced. It then requires a force exerted downwardly to move the bed to its fully horizontal open position. The hold-down or locking device, then, must be so arranged that it will overcome the force in the counter-balancing springs 47, tending to raise the bed to its neutral position 99.

Referring to Figs. 2 and 3, it is to be noted that the basin 72 projects into the room directly in the path of the bed, while the latter is being opened or closed. For this reason, it is necessary that the basin be closed when the bed is being moved in the vicinity of the basin. When the bed is in its neutral position 99" (Fig. 3) the basin 72 is accessible, because the bed is sufficiently removed from the floor area to permit the room occupant to use the basin. At the same time, the hopper 66 is available for use. When the bed is in its fully open position (indicated in broken lines 40' in Fig. 2) the hopper 66 is inaccessible for use by the room occupant, and if it were not for the locking device forming the subject matter of the present invention the wash-basin 72 would be available for use, because, as best shown in Fig. 2, the basin when opened assumes a position directly over the bed, and is very readily accessible to the occupant when he is on the bed.

The combination hold-down and locking device is shown in detail in Figs. 5 to 13, inclusive. It broadly comprises an elongated casing 100 (Figs. 5 to 8, inclusive), having a back 101 and a pair of sides 102 and 103 adapted to support a connecting rod member 104, and a locking lever 105. An actuating member 106 (Fig. 6) is supported on the transverse wall 29 of the room by means of a shaft 107 supported on a pair of spaced parallel supporting members 108 and 109 (Fig. 11) secured to the casing 100 and projecting inwardly

therefrom through an opening 110 in the wall 29. This actuating member 106 is pivotally mounted on the shaft 107 and comprises an outer face 111, which will be referred to as the actuating face, and an arcuate face 112, referred to as a hold-down face. At the rear edge of the hold-down face 112 is a downwardly projecting flange 113, which serves as a stop engaging a bumper 114 on the inner face of the casing 100. The actuating member 106 projects through an opening 115 in the outer face 101 of casing 100. Again referring to Fig. 11, the vertical supporting members 108 and 109 are connected at the rear thereof adjacent to their lower edges by a plate 116 and projecting inwardly from this plate is a lug 117. A second lug 118 projects inwardly from the inner face of the actuating member 106, and a coil compression spring 119 at its opposite ends surrounds the lugs 117 and 118, and being under compression forces the actuating member 106 away from the lug 117 to the position shown in Fig. 6. A projection 120 on the inner side of the hold-down face 112 engages the spring 119 to hold the latter in its proper relation with respect to the lugs 117 and 118, and a pin 121 connects spaced sides 122 of the actuating member 106 to restrict the upward movement of spring 119. At the top of the actuating member 106 is a hooked projection 123, which, together with the body portion of the actuating member 106 forms a slot 124. The actuating member 106 is adapted to rotate about the shaft 107 between the normal position shown in Fig. 6 and the releasing position shown in Fig. 10, a force applied on the actuating face 111 being necessary to rotate the member in a clockwise direction about the shaft 107 to overcome the force of spring 119. Upon releasing this force, the spring returns the actuating member 106 to its normal position shown in Fig. 6.

The connecting rod 104 (Figs. 5, 6, 8, 9, and 12) comprises a central, substantially straight shaft 125 having a curved hook portion 126 at the bottom thereof, and having a bifurcated portion 127 at its opposite end. Adjacent to this latter end of the rod 104 is a lug 128.

The locking lever 105 (see Figs. 5 to 9, inclusive) is pivotally mounted on a shaft 129, which projects from the casing 100. This shaft 129 is positioned between the ends of the lever 105, and one end of the lever is pinned at 130 to the bifurcated end of the connecting rod 104, and the other end 131 of the locking lever 105 is free to move from a position entirely within the casing 100, as shown in Fig. 5, to a locking position shown in Fig. 8, where the lock 105 projects beyond the end 132 of the casing 100. This free end 131 of the lock 105 is cammed at 133 (Figs. 8 and 9). Extending inwardly from the outer face 101 of the casing 100 are a pair of lugs 142 and 143 providing a recess 135 therebetween adapted to receive the lock 105, and the shaft 129 is secured to this projection 134 in the region of the recess 135. A closing plate 144 is secured to these lugs by means of machine screws 145 and forms the fourth side bounding the recess 135.

The connecting rod 104 is assembled in the casing 100 with its lower hooked end 126 entered in the slot 124 between the hooked projection 123 and the main body portion of the actuating member 106. This connecting rod is free to ride in the casing, and any downward movement of the rod applied on the hooked portion 126 thereof in response to movement of the hooked projection 123 of the actuating mem-

ber 106 rotates the lock 105 in a clockwise direction about the shaft 129, so as to move the lock from its position inside the casing, indicated in Fig. 5, to its locked position shown in Fig. 8. A spring 136 is concentrically mounted on a lug 131 extending inwardly from the face 101 of casing 100, and this spring is provided with a pair of arms 138 and 139, the former of which arms is hooked about a lug 140 projecting inwardly from face 101 of the casing 100, and the latter of which arms is hooked around the projection 128 on the connecting rod 104. This spring urges the connecting rod 104 and the remainder of the assembly into the position shown in Fig. 5, where the lock 105 is disposed wholly within the casing 100, and, in order to rotate the lock 105 to its locked position shown in Fig. 8, a downward force must be applied on the connecting rod 104 sufficient in strength to overcome the resistance of the spring 136. The spring 119 in the actuating member 106 helps spring 136 in maintaining the normal positions of the moving elements in the combination hold-down and locking device.

The complete combination hold-down and locking device just described is constructed as a unit entirely supported by the casing 100 and adapted to be mounted as a unit on the room wall 29. Referring to Fig. 1, this unitary device is clearly indicated at 141 and is mounted alongside the washbasin 72 with the edge 132 of the casing 100 disposed closely adjacent to the side of the basin recess, so that when the lock 105 (Fig. 8) is moved to its locked position, wherein it projects beyond the edge 132 of the casing, it overlaps the front face 79 of the basin 72. The combination hold-down and locking device 141 is fastened to the wall 29 by means of screws 147 passing through the casing 100 and into the wall. Other suitable means may be employed, if desired, for securing this member in place. Referring particularly to Fig. 9, the bed 40 is provided in its foot end 57 with a socket member 147 having outwardly extending flanges 148 and 149 which are secured to the foot end 57 of the bed. This socket has a downwardly sloping face 150.

Directly above the socket 147 is a U-shaped member 151 (Figs. 8 and 9) having a back portion 152 and a pair of spaced legs 153. Projecting through the U-shaped support 151 and into the socket 147 through an opening 153 in the upper face of the socket is a lever 154 pivotally mounted on the U-shaped supporting member 151 by means of a shaft 155 secured to the spaced legs 153 of the supporting member 151. The lever 154 extends downwardly in a substantially vertical direction below the pivot point 155 and terminates in an outwardly curved engaging portion 156. Above the pivot point 155 it extends substantially parallel to the end 57 of the bed and rises above the upper edge of the bed to furnish an arm 157 to be grasped by the occupant when releasing the bed from its horizontal position. A compression coil spring 158 is suitably held in place between the lower portion of the lever 154 and the foot end 57 of the bed, and this spring is under initial compression to hold the arm 154 in a position substantially parallel to the end 57 of the bed so that the lower curved portion 156 of the arm is disposed toward the rear of the socket 147. A force in a clockwise direction (Fig. 9) applied at the top of the lever 154 rotates the lever about the shaft 155 in a clockwise direction until it assumes the position indicated in broken lines at 154', in which position the lower curved

portion 156 of the lever projects outside the socket 147.

Referring to Fig. 2, the bed 40 is shown in solid lines in its daytime position in the recess 39. The seat 36 is available for use, as are the remaining facilities in the room, including the hopper 66 and the washbasin 72. The combination hold-down and locking device 141 is in its normal position with the actuating member 106 in its normal position shown in Fig. 6 and the lock 105 in its normal position entirely within the casing 100, as shown in Fig. 5. A basin 72 is unlocked and can be opened and closed at the will of the room occupant.

In order to open the bed 40 and lower it to its horizontal position for use, the basin 72 must first be closed. The bed is then lowered, and when it approaches its fully open position it strikes the actuating face 111 of the actuating member 106, as shown in Fig. 6 at 159, and then, as the bed is further lowered to its horizontal position, it rotates the actuating member 106 (Fig. 6) in a clockwise direction about the shaft 107, causing the hooked portion 123 of the actuating member to apply a downwardly directed force on the lower hooked portion 126 of the connecting rod 104. This downward movement of connecting rod 104 applies a clockwise torque on the locking member 105, causing this latter member to pivot in a clockwise direction about its axis 129, so as to move the locking member from its normal position, shown in Fig. 5, to its locked position, shown in Fig. 8. In its locked position, the locking member 105 partially projects over the front face of the basin 72, thereby locking the basin in its closed position.

When the bed 40 has been lowered to its fully open position, indicated in Fig. 9, it rests on the support 98, and the actuating member 106 projects into the socket 147 with the lower hold-down face 112 engaging the sloping face 150 of the socket 147 to apply a downward reaction onto the bed sufficient to overcome the effect of the counter-balancing springs 47 tending to raise the bed to its neutral position. Thus, the actuating member 106 serves as a hold-down member for locking the bed in its horizontal position, the lower curved portion 156 of the lever 154 serving as a stop for the actuating member 106 when it enters the slot 147, so that the actuating member 106 is not permitted to return to its normal position, shown in Fig. 6, but rather is permitted to rotate about its axis 107 in a counter-clockwise direction in response to the force applied by spring 119 a sufficient distance into the socket 147 to lock the bed in its horizontal position. At the same time the position of the hooked portion 123 of the actuating member is such that the connecting rod 104 holds the locking member 105 in its locked position shown in Fig. 8. As long as the bed 40 is in its horizontal position shown in Fig. 9, or in a slightly raised position where the lower flange 149 of the socket 147 is in the path of the actuating member 106, the basin 72 is positively locked by the locking member 105.

In order to release the bed to raise it to its closed position, the lever 154 is rotated in a clockwise direction (Fig. 9) about the shaft 155 by applying a force on the upper portion 157 of the lever. This movement of the lever causes the lower curved portion 156 thereof to force the actuating member 106 out of the socket 147, and by so doing the bed 40 can clear the actuating member 106, so that the force applied by the

counterbalancing springs 47 is effective in raising the bed. As soon as the bed 40 has been raised sufficiently to clear the actuating member 106, the spring 119 forces the actuating member to its normal position shown in Fig. 6, thereby unlocking the basin 72. In certain positions of the bed, however, during its initial stages of its raising movement, the bed itself obstructs the washbasin 72, so as to make it impossible to open the basin, such position of the bed being indicated in broken lines 99" in Fig. 3. It is not until the bed has been raised approximately to its neutral position, shown in broken lines at 99, in Fig. 2, that it is possible to gain access to the washbasin 72, but with the bed in this neutral position the hopper 66 has also become accessible. Thus, it is seen that at all times when the hopper 66 is rendered inaccessible by the bed 40 the washbasin 72 likewise is made inaccessible for use.

As shown, the combination hold-down and locking device 141 is applied directly to the face of the wall 29. A recess 160 (Fig. 7) in the side of the basin may be provided, which is of sufficient depth to permit the locking member 105 to enter the recess when it is in its fully locked position indicated in Fig. 7. In the event that the basin 72 is not fully closed when the bed 40 is lowered, the cammed face 133 of the locking member 105 cooperates with the slot 160 to close the basin sufficiently, when the lock is moved to its locked position, for this member to enter the slot 160 or to project partially across the front face 79 of the basin. This is a safeguard against breakage of the combination hold-down and locking device in the event the basin is not fully closed when the bed is lowered.

If desired, the casing 100 may be mounted inside the wall 29, so as not to be exposed on the outer face of the wall. In this event, a suitable slot in the side of the basin will be provided to cooperate with the locking member 105.

Obviously, modifications may be made without departing from the spirit of the invention. The important feature of the present invention is that in an arrangement of room facilities where the hopper is rendered inaccessible when the bed is open for use but normally the washbasin would be accessible at all times, the device functions automatically to render the basin inaccessible at all times when the bed is so disposed as to make the hopper inaccessible. One embodiment only of this invention has been shown for the purpose of disclosure.

A curtain 165 is provided to close the door opening into the room.

I claim:

1. In a room, the combination of a bed pivoted about a horizontal axis to permit raising and lowering of the bed between horizontal operative and vertical inoperative positions, a hopper in the room disposed relative to the bed so as to be rendered inaccessible when the bed is lowered, a pivoted washbasin in the room adapted to rotate from a horizontal operative to a vertical inoperative position, a locking device for holding the bed in its horizontal operative position and for locking the basin in its closed position at all times when the bed is lowered, said device comprising a movable lever engageable with the basin for locking same closed, an actuating member operatively connected to the lever and positioned in the path of the bed when the bed is moved between its two positions, and means on the bed cooperating with the actuating member for holding the bed in its horizontal position.

2. In a room, the combination of a bed movably mounted to assume operative and inoperative positions, a hopper in the room disposed relative to the bed so as to be rendered inaccessible when the bed is in operative position, a washbasin in the room movably mounted to assume operative and inoperative positions, a locking device including a basin locking member cooperating with the basin to hold the same in its inoperative position at all times when the bed is in its operative position, a releasable bed locking member engaged by and adjacent to the bed when it is in its operative position and cooperating therewith to hold the bed in its operative position, and means operatively connecting the bed and basin locking members to lock and unlock the basin when the bed is in its operative and inoperative positions respectively.

3. In a room, the combination of a bed movably mounted to assume operative and inoperative positions, a hopper in the room disposed relative to the bed so as to be rendered inaccessible when the bed is in operative position, a washbasin in the room movably mounted to assume operative and inoperative positions, a locking device including a basin locking member cooperating with the basin to hold the same in its inoperative position at all times when the bed is in its operative position, a releasable bed locking member engaged by and adjacent to the bed when it is in its operative position and cooperating therewith to hold the bed in its operative position, means operatively connecting the bed and basin locking members to lock and unlock the basin when the bed is in its operative and inoperative positions respectively, and readily accessible means operating on the bed locking member for releasing the bed to return same to its inoperative position and thereby unlocking the basin.

4. In a room, the combination of a bed movably mounted to assume operative and inoperative positions, a hopper in the room disposed relative to the bed so as to be rendered inaccessible when the bed is in operative position, a washbasin in the room movably mounted to assume operative and inoperative positions, a locking device including a basin locking member cooperating with the basin to hold the same in its inoperative position at all times when the bed is in its operative position, and a bed actuated member operatively connected to the basin locking member for moving said basin locking member to lock and unlock the basin, the bed actuated member being operated by the bed when the latter is moved to its operative position to lock the basin in its inoperative position, the actuated member unlocking the basin when the bed is moved toward its inoperative position.

5. In a room, the combination of a bed movably mounted to assume operative and inoperative positions, a hopper in the room disposed relative to the bed so as to be rendered inaccessible when the bed is in operative position, a washbasin in the room movably mounted to assume operative and inoperative positions, a locking device including a basin locking member cooperating with the basin to hold the same in its inoperative position at all times when the bed is in its operative position, a bed actuated member operatively connected to the basin locking member for moving said basin locking member to lock and unlock the basin, the bed actuated member being operated by the bed when the latter is moved to its operative position to lock the basin

in its inoperative position, the actuated member unlocking the basin when the bed is moved toward its inoperative position, and releasable means associated with the bed actuated member for locking the bed in its operative position.

6. A combination hold-down and locking device comprising an elongated casing, a lever pivoted to the casing adjacent to one end thereof and adapted to pivot from a position entirely inside the casing to a position projecting outside the casing, an actuating member pivoted to the casing adjacent to the other end thereof on an axis disposed at right angles to the axis of the lever, a connecting member operatively connected to the lever and actuating member and adapted to pivot the lever in response to movement of the actuating member, and resilient means normally holding the lever entirely within the casing.

7. A combination hold-down and locking device comprising a casing, a locking member movably mounted in the casing and in one position of its movement projecting from the casing, means for normally holding the locking member entirely within the casing, an actuating member pivotally mounted on the casing having an actuating face and movable with respect to the casing in response to a linear force on the said face, and means operatively connecting the actuating means to the locking member.

8. In a room, a bed foldable against one of the room walls and adapted to extend horizontally to the opposite room wall, a washbasin foldable against the last mentioned room wall, a combination hold-down and locking device on the said opposite room wall adjacent to the basin comprising a movable actuating member in the path of the bed when the latter is moved between its extended and folded positions, a movable lock cooperating with the basin to lock the basin in its folded position, means operatively connecting the actuating member to the lock, means on the bed cooperating with the actuating means to hold the bed in its extended position, and releasing means cooperating with the actuating means to release the bed so that it can be returned to its folded position.

9. In a room, a bed foldable against one of the room walls and adapted to extend horizontally to the opposite room wall, a washbasin foldable against the last mentioned room wall, a locking device on the said opposite room wall and adjacent to the basin comprising a movable actuating member in the path of the bed when the latter is moved between its extended and folded positions, a movable lock cooperating with the basin to lock the basin in its folded position, means operatively connecting the actuating member to the lock, and means on the bed engageable with the actuating means to lock the basin closed when the bed is extended and to unlock the basin when the said last named means is moved out of engagement with the actuating means.

10. An actuating member for use in a device of the class described comprising a main body portion having an inclined outer actuating face and a lower hold-down face extending at an angle with respect to said actuating face, a hooked projecting portion above the main body portion which with the body portion forms a slot between the hook and the main body portion, and supporting means on the hooked projection adapted to cooperate with a support for mounting the actuating member in pivotal relation.

11. An elongated case of the class described having a front face and rearwardly extending flanges surrounding the periphery of the face, the front face having an opening adjacent to one end of the case, and a pair of inwardly projecting parallel vertical flanges perpendicular to the front face one on each side of the opening, the peripheral flange having an opening adjacent to the opposite end of the case.

12. In a room, the combination of a bed pivoted about a horizontal axis to permit raising and lowering of the bed between horizontal operative and vertical inoperative positions, a hopper in the room disposed relative to the bed so as to be rendered inaccessible when the bed is lowered, a pivoted washbasin in the room adapted to rotate from a horizontal operative to a vertical inoperative position, the bed and the basin being so arranged with respect to each other that they move through intersecting arcs when pivoting from their operative to their inoperative positions, a locking device for holding the bed in its horizontal operative position and for locking the basin in its closed position at all times when the bed is lowered, said device comprising a movable lever engageable with the basin for locking same closed, an actuating member operatively connected to the lever and positioned in the path of the bed when the bed is moved between its two positions, and means on the bed cooperating with the actuating member for holding the bed in its horizontal position.

13. In a room, the combination of a bed in the room movable between operative and inoperative positions, a hopper in the room disposed relative to the bed so as to be rendered inaccessible when the bed is in operative position, a washbasin in the room movable between operative and inoperative positions, a basin locking member cooperating with the basin to hold the same in its inoperative position at all times when the bed is in its operative position, an actuating member operatively connected to the basin locking member adapted to move the said locking member so as to lock and unlock the basin, the actuating member being disposed in the path of the bed when the bed is moved between its operative and inoperative positions.

14. For use in a basin locking device wherein a locking member is moved in and out of locking engagement with the basin by movement of an actuating member, a connecting rod for conveying motion from the actuating member to the locking member and comprising an elongated shaft, a curved hook member at one end of the shaft adapted to engage the actuating member, a bifurcated portion at the other end of the shaft for securing the rod to the locking member, and a lug on the shaft adjacent to the bifurcated end thereof for anchoring thereon a spring.

15. In a room, a washbasin adapted to move between an operative, usable position and an inoperative, inaccessible position, a bed movable between operative and inoperative positions, a movable locking member adapted to lock the basin in its inoperative position, an actuating member operatively connected to the locking member and disposed in the path of the bed during the bed's movement between operative and inoperative positions, the bed engaging and operating the actuating member to manipulate the locking member.
